Specification of Letters Patent.

Patented Nov. 2, 1920.

Application filed August 13, 1919. Serial No. 317,174.

To all whom it may concern:

Be it known that we, ORTUS E. MOATS, a citizen of the United States, and a resident of Chicago in the county of Cook and State of Illinois, JAY B. RHODES, a citizen of the United States, and a resident of Kalamazoo, in the county of Kalamazoo and State of Michigan, and JAMES D. BENBOW, a citizen of the United States, and a resident of Aurora, in the county of Kane and State of Illinois, have invented certain new and useful Improvements in Grading-Machines, of which the following is a specification, reference being had to the accompanying drawings.

Our invention relates to road or grading machines of the type comprising a wheeled frame and a scraper mounted under the frame and arranged to be swung laterally and also to be adjusted angularly to the line of draft. It has for its primary object to provide a road machine with dirigible rear wheels mounted so that they may be shifted laterally with reference to the machine frame for the purpose of holding the scraper to its work when set in an angular position, and also for aiding in guiding the machine and varying the operating position of the scraper. Another object is to provide such a machine with means independent of the machine frame for steering such dirigible wheels. We accomplish these objects as illustrated in the accompanying drawings and as hereinafter described. What we regard as new is set forth in the claims.

In the accompanying drawings,

Figure 1 is a side elevation of the principal parts of a scraper embodying our invention, the wheels at the near side of the machine being omitted;

Fig. 2 is an enlarged detail, being a partial horizontal section on line 2—2 of Fig. 5;

Fig. 3 is a partial plan view of the rear portion of the machine frame showing the rear axle and the parts associated therewith;

Fig. 4 is a rear elevation of the parts shown in Fig. 3;

Fig. 5 is an enlarged detail, being a partial vertical cross-section on line 5—5 of Fig. 4;

Fig. 6 is an enlarged detail, being a partial vertical section on line 6—6 of Fig. 5;

Fig. 7 is a partial plan view showing a different form of locking device for locking the steering mechanism;

Fig. 8 is a rear elevation of the parts shown in Fig. 7; and

Fig. 9 is a partial longitudinal section on line 9—9 of Fig. 8.

In the embodiment of our invention illustrated in the drawings,—7 indicates the machine frame which is supported upon front wheels 8 and rear wheels 9. 10 indicates the usual scraper supporting frame which carries a scraper blade 11. These parts may be constructed and arranged in any approved way which will provide for angular adjustment of the scraper blade and also for its being swung laterally, and raised and lowered. The usual practice is to pivotally connect the forward end of the scraper supporting frame 10 to the machine frame so that it may be raised or lowered, or swung laterally, and to connect the scraper blade 11 with the scraper supporting frame 10 by means of a turntable 12 which may be rotated to vary the angular position of the blade. Suitable devices are mounted on the machine frame 7 for effecting the several adjustments, and in the illustration we have shown a shaft 13 provided with a hand wheel 14 for rotating the turntable 12, and a transversely mounted rack bar 15 and pinion 16 operated by a shaft 17 and hand wheel 18 for shifting the scraper supporting frame laterally, the connection between the shaft 17 and pinion 16 being preferably by a worm gear. For raising and lowering the scraper blade we provide hand wheels 19 at opposite sides of the machine operating through chains 20 and sprocket wheels 21 to vertically move connecting rods 22 which are attached at opposite sides to the rear end portion of the scraper blade 10.

So far as our present invention is concerned it is not essential that the devices shown for accomplishing the several adjustments of the scraper blade be used, as any other suitable means for the purpose may be employed.

23 indicates a platform provided at the rear end portion of the machine frame, as shown in Figs. 1 and 3. 24 indicates the rear axle of the machine, which is preferably composed of oppositely arranged chan-

nel beams 25—26 connected by top and bottom plates 27—28, as shown in Fig. 5, and is provided at its ends with yokes or forks 29 adapted to receive vertically disposed 5 pivots 30. Mounted upon these pivots are sleeves 31 which are connected with the spindles 32 for the rear wheels 9, as shown in Figs. 3 and 4. Projecting rearwardly from the sleeves 31 are arms or levers 33 by 10 means of which the sleeves 31 may be rocked upon the pivots 30 to turn the wheels 9 angularly with respect to the line of draft. 34 indicates a rack bar carried by the rear axle 24 at one side thereof, as shown in Fig. 15 2, and meshing with a pinion 35 mounted upon a vertically arranged shaft 36 having a hand wheel 37 by which it may be rotated, as shown in Figs. 1 and 2. The shaft 36 is 20 suitably mounted upon the machine frame, preferably by means of a bracket 38 shown in Figs. 1 and 2, and it will be apparent that by rotating the shaft 36 the rack bar 34 and with it the axle 24 will be moved endwise or transversely of the machine. As shown in 25 Fig. 4, the rear axle 24 is connected with the machine frame by clips or stirrups 39 which hold it up against the under side of the machine frame 7, and preferably rollers 40 are provided between the machine frame and the upper side of the rear axle to reduce 30 friction, as shown in Figs. 4 and 5. 41 indicates a longitudinally disposed rock-shaft which is journaled in a suitable housing 42 mounted on the rear axle 24, as shown in 35 Figs. 4 and 6, being preferably connected with said axle by a bracket 43, shown in Fig. 5. Said rock-shaft is provided with an arm 44 which is connected by a steering rod 45 with a cross-connecting rod 46 which 40 connects the two arms 33 at opposite sides of the machine so that the two rear wheels are steered in unison. Preferably the steering rod 45 is provided with ball and socket 45 connections at its ends, as shown in Fig. 4, but any other suitable connections may be employed. It will be apparent that by rocking the rock-shaft 41 the arm 44 may be 50 swung laterally, thereby steering the rear wheels through the rod 45. 47 indicates a segmental rack rigidly connected with the arm 44 so as to swing therewith and with the rock-shaft 41. Said rack is engaged by a latch lever 48 pivotally mounted on a supporting bracket 49 rising from the housing 42, as shown in Figs. 5 and 6, and normally held in engagement with said rack by a spring 50, as shown in Fig. 5. This latch serves to hold the rack 47 in the different 55 positions to which it may be adjusted; but by depressing the forward end of said latch lever the rack 47 may be released, thereby permitting the rock-shaft 41 to be rocked. By this construction the rear wheels may be set in different positions of angular adjustment so 60 that they will operate to hold the scraper 65

blade to its work when it is set at a more or less acute angle to the line of draft.

For the purpose of rocking the shaft 41 we preferably provide said shaft with a worm wheel 51 mounted in the housing 42 and meshing with a worm 52 carried by a vertically disposed shaft 53 also journaled in the housing 42 as shown in Fig. 6. This shaft carries a hand wheel 54, shown in Fig. 1, by which it may be rotated. It should be noted that the devices for steering the rear wheels and for locking such wheels in position are all carried by the rear axle so that when said axle is adjusted endwise they move with it, and the angular position of the rear wheels is consequently not disturbed by the movement endwise of the rear axle. These are important features of our invention and are claimed broadly.

For normally locking the rear axle against endwise movement a locking bolt 55 is provided, which is mounted to move vertically in the rear portion of the main frame and engages one of a number of holes provided in the upper plate 27 of the rear axle, 90 as shown in Fig. 5. A spring 56 serves to exert downward pressure on the bolt 55, and a foot lever 57 provides means for readily lifting the bolt 55 out of engagement with the rear axle when it is desired to 95 shift said axle endwise.

In Figs. 7, 8, and 9 is shown another form of locking device for locking the wheels in the different positions to which they may be adjusted. In the construction shown in said figures the cross-connecting rod 46 carries a locking plate 58 provided with a series of perforations, which plate extends between upper and lower plate 59—60 secured to the under-side of the bracket 43 and arranged to form a slotted frame, as best shown in Fig. 9. The plates 59, 60 are provided with aligned perforations adapted to register with one or another of the perforations in the plate 58 105 so that a bolt 61 passed through the perforations in the plates 58, 59, 60 may serve to lock the plate 58 in fixed relation to the bracket 43, thereby holding the cross-connecting rod 46 against endwise movement. 110 The bolt 61 is mounted to move vertically, being held by the plates 59, 60 and by a bracket 62 secured to the upper side of the housing 42, as best shown in Fig. 8. The bolt is moved endwise by means of a lever 120 63 mounted on a pivot 64 carried by the bracket 62, as shown in Fig. 8, and connected with the upper end of said bolt. Thus the lever 63 and the other parts of the locking mechanism are all supported by the 125 axle 24 and are independent of the frame of the machine, as is the case with the alternative locking mechanism shown in the other figures.

So far as we are aware, we are the first 130

in the art to provide a road machine having an endwise movable rear axle with dirigible rear wheels carried by such rear axle and provided with means independent of the machine frame for steering said wheels; also to provide means independent of the frame for locking the wheels in the different positions to which they may be adjusted. The claims hereinafter made directed to 10 these features are therefore intended to be generic.

What we claim as our invention and desire to secure by Letters Patent, is

1. In a grading machine, the combination 15 with a machine frame, of a transversely movable axle, wheels mounted on said axle and angularly adjustable relatively to the line of draft, and means independent of the machine frame for steering said wheels.

2. In a grading machine, the combination 20 with a machine frame, a scraper, and means for adjusting said scraper angularly relatively to the line of draft, of a transversely adjustable axle, wheels mounted on said 25 axle and angularly adjustable relatively to the line of draft, and means independent of the machine frame for adjusting said wheels relatively to the line of draft.

3. In a grading machine, the combination 30 with a machine frame, a scraper, and means for adjusting said scraper angularly relatively to the line of draft, of a transversely adjustable axle, means mounted on the machine frame for adjusting said axle end- 35 wise, wheels mounted on said axle and angularly adjustable relatively to the line of draft, and means independent of the machine frame for adjusting said wheels with relation to the line of draft.

4. In a grading machine, the combination 40 with a machine frame, of an endwise movable axle, wheels mounted on said axle and angularly adjustable relatively to the line of draft, means for steering said wheels, 45 and means independent of the machine frame for locking the wheels against angular movement.

5. In a grading machine, the combination 50 with a machine frame, a scraper, and means for adjusting said scraper angularly relatively to the line of draft, of an endwise movable axle, wheels mounted on said axle and angularly adjustable relatively to the line of draft, means for steering said wheels, 55 and means independent of the machine frame for locking the wheels against angular movement.

6. In a grading machine, the combination 60 with a machine frame, of a transversely adjustable axle, wheels mounted on said axle, and angularly adjustable relatively to the line of draft, and means mounted on said axle and independent of the machine frame for adjusting said wheels.

7. In a grading machine, the combination 65 with a machine frame, of a transversely adjustable axle, wheels mounted on said axle and angularly adjustable relatively to the line of draft, means for steering said wheels, and means mounted on said axle and independent of the machine frame for locking 70 said wheels against angular movement.

8. In a grading machine, the combination 75 with a machine frame, a scraper and means for adjusting said scraper angularly relatively to the line of draft, of a rear axle movable endwise transversely of the machine, wheel spindles carried at the ends of said rear axle and pivoted to turn the wheels 80 angularly relatively to the line of draft, wheels mounted on said spindles, means mounted on the machine frame for moving said axle endwise, and means independent of the machine frame for angularly adjusting 85 said wheel spindles.

9. In a grading machine, the combination 90 with a machine frame, a scraper and means for adjusting said scraper angularly relatively to the line of draft, of a rear axle movable endwise transversely of the machine, wheel spindles carried at the ends of said rear axle and pivoted to turn the wheels 95 angularly relatively to the line of draft, wheels mounted on said spindles, means mounted on the machine frame for moving said axle endwise, and means mounted on the axle and moving therewith for angularly adjusting said wheel spindles.

10. In a grading machine, the combination 100 with a machine frame, a scraper and means for adjusting said scraper angularly relatively to the line of draft, of a rear axle 105 movable endwise transversely of the machine, wheel spindles carried at the ends of said rear axle and pivoted to turn the wheels angularly relatively to the line of draft, 110 wheels mounted on said spindles, means mounted on the machine frame for moving said axle endwise, and means independent of the machine frame for locking said wheel spindles against angular adjustment.

11. In a grading machine, the combination 115 with a machine frame, a scraper and means for adjusting said scraper angularly relatively to the line of draft, of a rear axle 120 movable endwise transversely of the machine, wheel spindles carried at the ends of said rear axle and pivoted to turn the wheels angularly relatively to the line of draft, wheels mounted on said spindles, means mounted on the machine frame for moving said axle endwise, and means mounted on the axle and moving therewith for locking 125 said wheel spindles against angular adjustment.

12. In a grading machine, the combination 125 with a machine frame, of a transversely adjustable axle, wheels mounted on said axle

and angularly adjustable relatively to the line of draft, means mounted on the machine frame for moving said axle endwise, and means independent of the machine frame for 5 steering said wheels, comprising a rock-shaft having an arm connected with the wheels, and a worm and worm wheel for rocking said rock-shaft.

13. In a grading machine, the combination 10 with a machine frame, of a transversely adjustable axle, wheels mounted on said axle and angularly adjustable relatively to the line of draft, means mounted on the machine frame for moving said axle endwise, and 15 means independent of the machine frame for steering said wheels, comprising a rock-shaft having an arm connected with the wheels for angularly adjusting the same,

and means mounted on the axle for locking said wheels in position. 20

14. In a grading machine, the combination with a machine frame, of a transversely adjustable axle, wheels mounted on said axle and angularly adjustable relatively to the line of draft, means mounted on the machine 25 frame for moving said axle endwise, and means mounted on said axle for steering said wheels, comprising a rock-shaft having an arm connected with the wheels for angularly adjusting the same, and means mounted on the axle for locking said wheels in position. 30
